UNITED STATES PATENT OFFICE.

ERNEST S. CLEVELAND AND GEORGE G. LEFFINGWELL, OF CHICAGO, ILLINOIS.

ARCH SUPPORT.

Application filed December 11, 1920. Serial No. 429,883.

To all whom it may concern:

Be it known that we, ERNEST S. CLEVELAND and GEORGE G. LEFFINGWELL, both citizens of the United States, and residents of Chicago, in the county of Cook and State of Illinois, have invented certain new and useful Improvements in Arch Supports, of which the following is a full, clear, and exact description.

10 The invention relates to arch-supports.

Heretofore, it has been the practice to provide arch-supports under the foot which were operative only when supported by a shoe. The primary object of the invention is to provide an improved arch-support which will be operative at all times and effective in supporting the arch when a shoe is not being worn, that is, when the person affected is asleep or lying down, as well as when a shoe is on the foot. As a result of providing a constantly operative support, strengthening of the arch will be expedited, because of its beneficial effect while the person is lying down or asleep. 25 A further object of the invention is to provide an improved arch-support of this character which is suspended from a portion of the body above the ankle and in such a manner that it will not arrest or retard the blood-supply to the foot.

30 The invention consists in the several novel features hereinafter set forth and more particularly defined by claims at the conclusion hereof.

35 In the drawings: Fig. 1 is a perspective of a support embodying the invention when the retaining loop has been placed around the arch and before the suspension means has been secured to the leg. Fig. 2 is a similar view showing the supporting strap wrapped around the back of the leg and laid under the foot-arch and before the attaching device has been secured to the leg. Fig. 3 is a similar view showing the support completely attached to and operative on the leg. Fig. 4 is a detail of the support, the covering sleeve being shown in section.

40 The improved arch-support comprises a flexible strap 5, usually formed of non-elastic webbing and having an eye 6 at one end through which the strap extends to form a loop 7 adapted to pass completely around the arch of a foot to attach the lower end of the support to the foot. The strap

5 extends upwardly from the attaching loop 7 and is of sufficient length to extend around the back of the foot, as at 18, and form a second or supporting loop 9 under and around the arch. The free end of the strap 5 is connected to an elastic suspension-strip 10. The ends of the strip 10 and strap 5 are permanently secured together. The upper end of the elastic 10 is adjustably connected by a buckle 11 to an attaching piece 12 which is faced on one side with adhesive plaster 13 by which it may be secured to the leg above the ankle and preferably below the knee. A chamois sleeve 14 is slidably fitted around the strap 5 to prevent that portion of the strap which underlies 70 the arch from abrading or cutting the skin of the foot.

When the improved support has been applied and the attaching-piece 12 secured to the leg, as illustrated, the loop 9 will be suspended from above by means of the elastic strip 10 which will exert a constant elastic pull upon said loop and will serve as a suspension-support for the arch of the foot. The improved support is adapted to be worn at all times so that it will have a supporting effect at all times, even when the wearer is lying down or asleep in bed and, as a result, the improved support will be constantly effective to remedy weakness in 85 the arch. The suspension device described exemplifies one which will support the arch without any constriction of the leg or arresting or retarding the blood-supply. The lifting effect is elastic at all times and localized pressure is avoided. A support which is operative while the wearer is in bed has been found to be effective in rebuilding the arch.

90 The invention is not to be understood as restricted to the details set forth, since these may be modified within the scope of the appended claims, without departing from the spirit and scope of the invention.

Having thus described the invention, what we claim as new and desire to secure by Letters Patent, is:

1. An arch support comprising a non-elastic strap adapted to be wrapped around and secured on the foot and to be extended under the arch, an elastic substantially flat suspension strip having one of its ends secured to the upper end of the non-elastic

strap and of sufficient length to extend vertically and around a leg and means connected to the other end of the suspension strip and adapted to be secured to a portion of the body above the ankle.

2. An arch support comprising a non-elastic strap provided at one end with an eye and extended through the eye to form an expansible and contractible slip-loop 10 adapted to pass around the foot and around the back of the foot under the arch, and suspension means adapted to be secured to a portion of the body above the ankle and connected to the other end of the strap.

15 3. An arch-support comprising a non-elastic strap adapted to be wrapped around and secured on the foot and extended under the arch, a protective sleeve slidable on the strap, and suspension means adapted 20 to be secured to a portion of the body above

the ankle and connected to the upper end of the strap.

4. An arch-support comprising a strap adapted to pass under the arch, a suspension device connected to the strap, and an attaching-piece connected to the upper end of the suspension device and provided with an adhesive face whereby it may be secured directly to a portion of the leg above the foot.

5. An arch-support comprising a strap 25 provided with a loop at one end for attaching it to a foot and extended from the loop to pass around the back of the foot and thence around and under the arch to form a support, an elastic strip to which the other 30 end of the strap is connected, and an adhesive attaching piece adjustably connected to said elastic strip.

ERNEST S. CLEVELAND.
GEORGE G. LEFFINGWELL.
